United States Patent Office.

FREDERICK ROBBIN, OF HUDSON CITY, NEW JERSEY, ASSIGNOR TO HIMSELF AND PHILIP LAHR, OF NEW YORK CITY.

Letters Patent No. 96,966, dated November 16, 1869.

IMPROVED WRITING-DESK.

The Schedule referred to in these Letters Patent and making part of the same.

To all whom it may concern:

Be it known that I, FREDERICK ROBBIN, of Hudson City, in the county of Hudson, and State of New Jersey, have invented a new and useful Improvement in Convertible Writing-Desks; and I do hereby declare that the following is a full, clear, and exact description thereof, which will enable others skilled in the art to make and use the same, reference being had to the accompanying drawing, forming part of this specification.

This invention relates to a new and useful improvement in writing-desks, whereby they are made much more useful than desks of ordinary construction, and consists in so constructing and arranging the top and the case containing the drawers and pigeon-holes that a writing-desk or a table may be formed at will, as will be hereinafter more fully described.

In the accompanying drawings—

Figure 1 represents a vertical section, showing the parts arranged as a table, with the case dropped beneath the top.

Figure 2 is a vertical section, showing the parts arranged as a desk.

Similar letters of reference indicate corresponding parts.

A is the top, and

B is the case containing the drawers and pigeon-holes.

C represents the frame or body, to which legs may be attached.

D represents slotted curved plates attached to the top on each side.

E is a sector-plate pivoted to each side of the frame C, on which the bottom of case B rests.

It is by moving this sector-plate back and forth on its pivot that the case is raised, as seen in fig. 2.

F is a rod, which connects the sector-plate E with the slotted plate D.

As the top A is drawn out or forward, the wrist-pin G, by which the rod is attached to the slotted plate D, slides in the slot and draws up the sector-plates and raises the case.

H represents a support for the top, (on each side,) which is pivoted to the frame at I, and connected with the sector-plate at I', so that when that plate is raised,

as seen in fig. 2, the support is raised and holds the top in an inclined position, as seen.

J represents lugs on the sector-plates upon which the case rests.

There are hooks K on the supports H, which fasten to the top when the top is in the position seen in the drawing, fig. 2, and which hold the top in place and prevent it from tipping down in bearing upon its front edge.

The case falls by its own gravity when the sector-plates are turned down, as seen in fig. 1.

To convert the desk into a table, the top is drawn back from the hooks K, and raised while it is pressed back, so as to force back the plates E.

As the plates E turn back, the case follows until it drops entirely within the frame, as seen in fig. 1.

The top A then assumes a horizontal position, and a table is produced suitable for all ordinary purposes.

When the top A is in the inclined position, it may be drawn from the hook K and raised sufficiently to give access to the compartment beneath it.

On the back of the frame there are hooks, L, with which the back of the top engages, as it does with the hooks K.

This arrangement keeps the top secure when locked and in the table form.

Having thus described my invention, I claim as new, and desire to secure by Letters Patent—

1. The arrangement of the top A and case B, in combination with the frame C, whereby the desk or the table is formed, as described.

2. In combination with the convertible desk, the sector-plates E, whereby the case B is raised, as described.

3. The supports H, in combination with the rods F and plates E, as and for the purposes set forth.

4. The combination of the plates E, rods F, slotted plates D, case B, and top A, arranged and operating as described, for the purposes specified.

The above specification of my invention signed by me, this 6th day of October, 1869.

Witnesses: FREDERICK ROBBIN.

GEO. W. MABEE,

ALEX. F. ROBERTS.
